PAPER TOWEL DISPENSER

Riley H. Brooks, 1522 1st St., Webster City, Iowa 50595

Filed Nov. 12, 1970, Ser. No. 25,952

Term of patent 14 years

Int. Cl. D20—02

U.S. Cl. D52—2

Fig. 1

Fig. 2

Fig. 3

Fig. 4

FIG. 1 is a frontal perspective view of a paper towel dispensing device showing my new design;

FIG. 2 is a top plan view thereof;

FIG. 3 is a front elevational view, the rear being substantially a mirror image thereof;

FIG. 4 is a left end elevational view, the right end being a mirror image thereof.

I claim:

The ornamental design for a paper towel dispenser, substantially as shown and described.
